UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

PAPER-FEED MECHANISM.

1,207,630.

Specification of Letters Patent.

Patented Dec. 5, 1916.

Application filed June 1, 1915. Serial No. 31,333.

To all whom it may concern:

Be it known that I, ALVAH C. ROEBUCK, a citizen of the United States, residing at Woodstock, in the county of McHenry and State of Illinois, have invented certain new and useful Improvements in Paper-Feed Mechanism, of which the following is a specification.

This invention relates to a typewriter machine, and more particularly to that part of a machine known as the paper feed mechanism.

The principal object of the invention is to provide an improved construction, combination and arrangement of parts for holding, feeding and adjusting the paper with respect to the platen.

Other objects will appear hereinafter.

In the drawings, Figure 1 is a front elevation of a portion of a typewriter platen and the parts appertaining to this invention, and Fig. 2 is a sectional view of part of the mechanism shown by Fig. 1.

In a typewriter the paper apron which extends under the platen is pressed yieldingly against the platen for the purpose of holding the paper in position with respect to the platen. Means is also provided for withdrawing the apron from the platen and for permitting the apron to move yieldingly away from the platen to accommodate various thicknesses of paper. In the present construction a platen 1 is rotatably mounted in end plates 2 of a typewriter sub-carriage which are held together by bars 3, 4 and 5. A rotatable bar 6 is also mounted in the end plates 2, and pivoted on one of the end plates is an operating lever 7 which is connected to the bar 6 for oscillating it by means of a link 8 and an arm 9 secured to the bar 6.

A paper apron 10 is bent to substantially conform to the curvature of the platen and has depending ears 11 at the rear in which a shaft 12 is mounted, and depending ears 13 at the forward end in which a shaft 14 is mounted. Mounted upon these shafts are paper feeding rollers being suitably spaced apart as by means of sleeves 17. Intermediate the ears 11 and 13 are depending ears 18 each of which is formed with a slotted perforation, and connected to the rotatable bar 6 are arms 19 which are each loosely secured to one of the ears 18 by means of a fastening device 20. Pivoted

mounted on the front shaft 14 is a plate 21 which is pressed yieldingly against the platen by means of a coil spring 22 at each end of and surrounding the shaft 14. This plate may be provided with graduations, as shown in Fig. 1, for determining the length and position of the printing line.

Secured to the frame bar 4 is an abutment 22' through which an adjustable screw 23 is threaded with a projection 24 at its inner end about which a loop 25 of a spring 26 is passed for holding the spring in position. This spring 26 is also wound about the bar 6 and has another bent extremity 27 which bears directly against the paper apron 10 adjacent the ear 18 at each end of the apron, the extremity being bent around the ear.

A paper table 28 is pivoted in the end plates 2 at the rear of the platen and bears normally against one of the frame bars 3 so that it forms an extension and guide for directing the paper between the paper apron and the platen. The paper apron is formed with openings through which the rollers 15 and 16 extend so that when paper is inserted between the apron and the platen it is engaged by the rollers and the apron is forced away from the platen against the tension of the spring 26. With the spring bearing against the apron intermediate of the rollers 15 and 16 it is obvious that the spring 26 will press either the front or back rollers separately against the platen or will press them both against the platen through the apron itself, and the plate 21 which is pivoted on the front shaft 14 will be pressed by its spring in the direction of the platen regardless of the position of the front or rear of the apron, thus assisting in holding the bottom edge of the paper against the platen when it is desired to print a line adjacent the bottom of the sheet.

The construction is very simple, inexpensive, and unlikely to get out of order. The tension of each spring may be easily varied, and the extremity of the spring which bears directly against the apron may be easily bent to change the point of actual contact with the apron, thus varying the point of application either to the front or rear of the point shown in Fig. 2. In this way the pressure of the front and rear rollers may easily be varied.

What I claim is:

1. In a typewriter, a platen, a paper apron

extending thereunder, a movable support for the apron comprising a rock shaft loosely connected with the apron, a fixed abutment, and a spring extending around 5 the said shaft having one end in engagement with the abutment and the other end bearing directly upon the paper apron.

2. In a typewriter, a platen, a paper apron extending thereunder, a movable support 10 for the apron comprising a rock shaft and arms on the shaft loosely connected with the apron, a fixed abutment, and a spring having one end supported by the abutment and the other end bearing directly upon the 15 apron to press it toward the platen.

3. In a typewriter, a platen, a paper apron extending thereunder, a movable support for the apron comprising a rock shaft and arms secured to the rock shaft having a 20 loose connection with the apron, an abutment adjacent each end of the apron, and a spring having one end supported by the abutment and the other bearing directly against the under side of the apron.

25 4. In a typewriter, a platen, a paper apron extending thereunder, a movable support for the apron comprising a rock shaft and arms secured thereto loosely connected with the apron, an abutment adjacent each end 30 of the apron, an adjusting screw threaded in the abutment, and springs one at each end of the apron having one looped end in engagement with the adjusting screw and the other end bearing against the paper 35 apron.

5. In a typewriter, a platen, a paper apron extending theretnder, a support for the apron comprising a rock shaft, arms secured to the rock shaft having a loose connection 40 with the paper apron adjacent the ends, a fixed abutment and adjacent each end of the paper apron, an adjusting screw threaded in the abutment, a spring wound about the shaft at each end having one extremity 45 engaged by the adjusting screw in the abutment and having the other end extending along one of the said arms and bearing directly upon the under side of the apron, a pivoted finger lever, and a link connecting 50 the finger lever to oscillate the rock shaft whereby the apron may be moved yieldingly away from the platen against the tension of the said spring when the loose connection is taken up.

55 6. Paper feeding mechanism comprising a platen, a paper apron extending thereunder having ears bent downwardly at the front, rear and at an intermediate point at both ends of the apron, front and rear paper 60 feed rollers mounted respectively in the front and rear depending ears and adapted to bear against the platen, means to loosely engage the intermediate ears of the apron

to move it bodily away from the platen, and a single spring adjacent each end of 65 the apron bearing directly upon the under side of the apron at a point adjacent the intermediate ears tending to press the entire apron in contact with the platen.

7. Paper feeding mechanism comprising 70 a platen, a paper apron extending thereunder having ears bent downwardly at the front, rear and at an intermediate point adjacent the ends of the apron and with openings through the apron in line with the 75 front and rear ears, a shaft mounted in the rear ears, feed rollers mounted on the shaft, another shaft mounted in the front ears, feed rollers mounted thereon and spaced apart, a spring-pressed plate mounted on 80 the front shaft the upper edge of which bears against the platen, means for moving the apron bodily toward and from the platen comprising a rock shaft, arms secured thereto having a loose connection with 85 the intermediate depending ears of the apron, a lever, means connecting the lever to rock the shaft, an abutment fixed adjacent each end of the apron, an adjusting screw threaded in each abutment, and a 90 spring wound about the rock shaft adjacent each end having one looped extremity in engagement with the adjusting screw and the other extremity extending along the said 95 arm adjacent thereto and bent about the ear to which arm is connected bearing directly upon the under side of the apron for pressing it and the rollers in the direction of the platen.

8. In a typewriter, a platen, a paper 100 apron extending beneath the platen, paper feed rolls mounted at the front and rear of the platen, a movable support for the apron having a loose connection with it intermediate the front and rear, and a spring having a bendable end to engage the under side of the apron and press it toward the platen, the end being bendable to vary the point of application intermediate the front and rear thereby varying the pressure on the front 110 and rear paper rolls.

9. In a typewriter, a platen, a paper apron extending thereunder, means loosely connected to each end of the apron for withdrawing it from the apron, a fixed abutment 115 below the apron, and a spring extending between the abutment and the apron tending to press it against the platen.

In testimony whereof I have signed my name to this specification, in the presence of 120 two subscribing witnesses, on this 28th day of May, A. D. 1915.

ALVAH C. ROEBUCK.
